UNITED STATES PATENT OFFICE

EBER J. HAYMAN, OF PARKERSBURG, WEST VIRGINIA

LOCKING SHEET METAL STRUCTURE

Application filed March 10, 1932. Serial No. 597,929.

My present invention relates to a lock or latch for sheet metal structures and is particularly applicable and useful for stovepipe sections.

5 The principal object of the invention is to provide a pipe section with a longitudinal lock or latch which will be adequately secure against accidental separation but which may be unlocked or unlatched when necessary 10 without the use of tools and without mutilation of the section.

In locking stovepipe sections heretofore placed on the market, locks or latches have been provided along adjacent longitudinal 15 edges thereof either at spaced apart intervals or substantially continuously along the entire edge. In the first instance, due to the fact that the section was secured together only at spaced apart points, the general public has 20 felt some hesitancy in being entirely satisfied therewith, due to the fear that should one or more latches become unfastened, the entire section might collapse. This sales resistance does not exist however to those sections where 25 the entire longitudinal edge constitutes a latch or lock. The difficulty with this latter type of pipe, however, is that once latched together, the edges cannot readily be separated without the use of special tools, or in the absence 30 thereof, without springing or mutilation of the folds constituting the section edge portion. Even though such latches are not capable of ready separation, they do permit a certain amount of undesirable relative longitudinal 35 movement between the two edges locked together. This movement tends to throw the section or sections out of alignment.

It is, therefore, one of the objects of the present invention to overcome the above defects.

To this end the invention contemplates in its broadest aspect a stovepipe section having a longitudinal locking seam in which the tendency to separate is resisted at substantially 45 every point along the seam in contradistinction to only a few points as in the case of isolated or spaced apart latches. In addition, such latch as here contemplated is capable of ready separation when desirable, but 50 incapable of any great amount of relative

longitudinal movement of its two component parts. This, of course, without the use of extraneous fastening devices such as rivets, screws, bolts or the like.

One form of the invention may consist of 55 folding one longitudinal edge portion of a sheet upon itself to form three thicknesses of material, the last fold having a portion projecting outwardly beyond the thus folded edge. An angular shoulder is formed in this 60 projecting portion, spaced from the folded edge. With this female portion, the other or male edge portion of the sheet co-operates. The latter consists of two folds substantially 65 at right angles to each other to form a locking shoulder and an extension projecting beyond the shoulder. This projection is adapted to be received between two of the folds of the female portion so that the locking shoulders of each part engage each other and 70 prevent separation.

Means are provided to permit ready separation of the locking parts when desired which at the same time prevents undesirable relative longitudinal movement therebetween. Such means may consist of a boss 75 on one of the complementary parts projecting through or into an opening in the other part. As shown, the boss is provided with sloping end portions which permits the two locking edges to ride up on each other when force is exerted longitudinally but which will maintain the parts immovable longitudinally until such force is deliberately applied. Having ridden up on each other, 80 the two locking edges may now be readily separated by pulling them away from each other.

The invention further consists in the novel combination, construction and arrangement 85 of parts more fully hereinafter described and shown in the accompanying drawing.

Fig. 1 is a view of a section according to this invention.

Fig. 2 is an end view of the section of 90 Fig. 1.

Fig. 3 is a sectional view along the line 3-3 of Fig. 1.

Fig. 4 is a sectional view of the parts approaching latching position. 100

Fig. 5 is a plan view showing the latch disengaged.

Fig. 6 is a view of a modified form.

Fig. 7 is a view along the line 7—7 of Fig. 6.

5 In the drawing, the two female and male complementary locking edge portions are indicated generally at A and B, respectively. The part A is provided with folds forming 10 three thicknesses of material, 1, 2 and 3, thicknesses 2 and 3 being on the inside or axis side of the pipe. The fold 3 is provided with an outwardly extending portion 4 and a laterally extending portion 5, the portion 4 15 constituting a locking shoulder, this shoulder being spaced slightly from the folded edge 7 of the part A. It is to be noted that the locking shoulder 4 extends substantially the entire length of the section.

20 The male part B is folded twice, each fold being substantially at right angles to each other to form the part 8 and the extension 9, the former constituting a locking shoulder adapted to engage the locking shoulder 4 25 when the parts A and B are mated and interlocked. The fact that the shoulder 4 is spaced slightly from the folded edge 7, permits the extension 9 to be readily inserted therebetween when the section is to be latched together.

30 From the above, it will be apparent that when once snapped together, it is extremely difficult for the parts A and B to be completely separated from each other without either 35 lifting up the folds 1 and 2 to clear the juncture of folds 8 and 9, or to depress the fold 5 to clear the parts 8 and 9. In either event, the latch must be unduly distorted and mutilated. For this reason, means are provided 40 to permit separation of the parts when desired. It is also to be noted that with only the mechanism above described, the parts A and B may slide longitudinally a considerable distance relative to each other and 45 that such movement would throw the entire section out of alignment. This undesirable movement is prevented by the same instrumentality which permits separation of the parts, and comprises the following.

50 In the modification shown in the drawing, the extension 9 in part B is provided with an offset boss 10 which when the parts are in full latched position, projects toward the axis of the pipe and into a corresponding 55 opening 11 in part A. Obviously this opening may be either an actual space or slot cut or punched out of the part A or an offset 12 may be provided as shown in Figs. 6 and 7. In either event, the boss 10 is provided with 60 sloping end shoulders 13 so that when the two edge portions A and B are forced to move longitudinally, the boss 10 will ride under the innermost fold 3 and separate the folds 3 and 2 to such an extent that the parts 65 A and B may then be withdrawn from lock-

ing engagement. However, as the boss 10 increases in height toward the extreme edge of the fold or extension 9 to an appreciable extent, it requires deliberately applied force to cause this extent of movement. As a result, the boss and its complementary recess prevent any tendency toward accidental relative longitudinal movement. By extending the slot or offset beyond the shoulder in the part B, a gap or opening 14 is provided which 70 facilitates entering of the boss into the part A when the complementary edges of the section are mated.

I claim:

1. A locking stovepipe section having two mating edge portions, one edge being folded upon itself to form three thicknesses of material, two of which are on the inside of the pipe, the innermost fold having a portion extending outwardly toward the periphery 80 of the pipe to form a longitudinal locking shoulder spaced from the adjacent folded edge of the two outside folds, the innermost fold having a recess therein, the other mating edge portion having a complementary 85 longitudinal locking shoulder and an extension beyond the shoulder, with a boss on said extension, the two locking shoulders being adapted to engage each other and the boss being adapted to project into the recess when the said shoulder extension is located between the said innermost and intermediate folds.

2. The device of claim 1 in which the boss is provided with sloping end portions.

3. The device of claim 1 in which the recess comprises a slot.

4. The device of claim 1 in which the height of the boss is greater than the normal distance between the intermediate and innermost folds.

5. The device of claim 1 in which the height of the boss increases in a direction toward the extreme edge of the shoulder extension.

6. The device of claim 1 in which the recess comprises a portion offset from the plane of the innermost fold.

7. The device of claim 1 in which the recess constitutes an offset portion similar to but of larger proportions than the boss.

In testimony whereof, I have hereunto subscribed my name this 2nd day of March, 1932.

EBER J. HAYMAN.
